ELECTRIC WALL PLATE

Arthur J. Pulos, Syracuse, N.Y., assignor to Pass & Seymour, Inc., Syracuse, N.Y., a corporation of New York

Filed Oct. 30, 1962, Ser. No. 72,307

Term of patent 14 years

(Cl. D26—13)

FIG. 1

FIG. 2

FIG. 3

FIGURE 1 is a front elevation of an electric wall plate; embodying my new design;

FIGURE 2 is a side elevation thereof; and

FIGURE 3 is a bottom plan view thereof on the same scale as FIGURES 1 and 2.

The dominant features of my design reside in the portions shown in solid lines.

The essential features of the design as shown in full lines include the flat edges of substantial height bordering the whole wall plate and extending at right angles to the plane of its back face, those on the long sides met by flat chamfers of about the same depth which form sharp edges with the plane side panels of the front face, the ends of these panels, however, being rounded to meet the flat

edges on the plate ends, and, the central scoop between the panels having a bottom plane throughout its length, substantially meeting the tops of the flat edges on the ends and curved upwardly on a small radius to meet the inner edges of the panels, all as shown.

I claim:

The ornamental design for an electric wall plate, substantially as shown and described.
